Attorney:

UNITED STATES PATENT OFFICE

FRANK W. ROBINSON, OF READING, PENNSYLVANIA, ASSIGNOR TO SCHUYLKILL HOSIERY MILLS, OF READING, PENNSYLVANIA, A CORPORATION OF PENNSYLVANIA

STRIPING ATTACHMENT FOR CIRCULAR KNITTING MACHINES

Application filed April 16, 1929. Serial No. 355,605.

My invention relates to circular knitting machines, and more specifically to a striping thread attachment therefor of the kind set forth in my prior Patent No. 1,428,398, of September fifth, 1922, and comprises mainly improvements in the construction, driving mechanism, and automatic pattern control mechanism of said striping attachment and certain related parts, whereby I am enabled to produce a greatly increased variety of pattern designs not heretofore attainable. More concretely my improvements provide, among other advantages that will later herein appear, for shifting the striping thread guide fingers from one set of striping needles to another during such stripe formations, and for automatically controlling such guide shifts from the pattern mechanism. The nature of my improvements and the advantages thereof are fully set forth in the following specification in connection with the accompanying drawing, and the novel features thereof pointed out in the appended claims.

In the drawing,—

Fig. 1 is a sectional elevation showing my improved construction in preferred form, in connection with known knitting machine elements, the view being largely diagrammatic.

Fig. 2 is a separate perspective view of the reel driving ring gear, partly in broken away sections.

Fig. 3 is a corresponding broken away sectional perspective view of part of the bobbin carrying reel.

Fig. 4 is a developed diagrammatic elevation of the cam ring, showing the needle lowering mechanism for certain of the raised striping thread needles.

Fig. 5 shows a knitted stocking having a striping design produced with my improved construction.

The knitting machine and striping attachment shown in the drawing are similar in their main features and operation to those more fully set forth in my prior patent above referred to, and comprise a usual rotary nee-

dle cylinder 2, certain of the circular series of needles 3 carried thereby having operative varyingly-butted jacks 4 acted upon by a series of jack cams 5, the different movements of the latter being controlled as heretofore by pattern mechanism to selectively raise determined needles into feeding position to receive the threads from the several guide fingers 6 of the striping attachment, which fingers 6 have needle-engaging swinging movements controlled by pattern mechanism, all as more fully described in my aforesaid patent. In the known mechanism above briefly referred to, the several guide fingers 6 are maintained in constantly fixed relation relative to the needle cylinder, and each finger 6 therefore feeds its thread only to its own respective needles throughout the striping operation.

Having in mind the previously stated provision for varying the series of needles fed by the several guide fingers 6, my invention relates primarily to improvements in the carrier mechanism for said fingers and to novel driving means for said carrier as will now be fully described, referring to the preferred construction shown in the drawing.

A pillar 12, supported on the machine frame, is shown as having an upper bracket 13, in the outer end of which is fixedly suspended a carrier rod 15 non-rotatably depending in vertical alinement with the axis of the needle cylinder 2. Rotatably mounted on the upper end of said rod 15, is a bobbin carrying reel or spool 16, preferably comprising as shown, upper and lower disc members 17 and 18, respectively, held in spaced relation by a central rod engaging spindle 19 and radial partitions 20, the latter separating the several bobbins 21 which are mounted on the lower disc member 18. A concentric ring 22 is shown as fixedly suspended below disc member 18 to provide a support for proper tension devices for the several threads, the latter as indicated, ex-

tending from the several bobbins 21 upwardly through eyelets in the disc member 17, thence downwardly through other eyelets in said disc 17, and eyelets in disc 18, and ring 22 to the guide fingers 6 below the latter.

The guide fingers 6, as indicated, are similar in construction to those shown in my aforesaid prior patent, and are pivotally mounted in a carrier head 25 as before, said head in the present instant however, merely loosely engaging rod 15 and being rotatably supported in spaced relation beneath ring 22 by a bearing ring 26 formed in the end of a bracket 27 carried by pillar 12. Rigid arms 28 are shown as operatively connecting said head 25 to ring 22, so that it will be understood that said head and ring and bobbin carrying reel 16 will rotate as a unit on rod 15.

The needle-engaging swings of the guide fingers 6 are effected as heretofore by a vertically movable cam sleeve 30 acting in the manner set forth in my aforesaid patent, said sleeve in the present construction being mounted between ring 22 and head 25 and having an integral spline slidably engaging a vertical groove in rod 15, said groove extending lengthwise of said rod and carrying a rigid spline extension 31, the projecting upper end of which is formed with a head 32 engaged by the forked end of a cam-sleeve positioning lever 33 pivotally mounted on bracket 13. The lever 33 has pivotally connected thereto a link 34 connecting it with the pattern control mechanism to determinately control the needle engaging swings of the several guide fingers 6 as heretofore.

In the improved construction above set forth, it will be noted that the finger carrier head 25 and its connections are free from any connection to the needle cylinder 2 and may be independently rotated to vary the relative positions of the several guide fingers 6 to the circle of needles, or may be driven jointly with said cylinder to maintain a fixed relation as heretofore.

The improved driving means for said head 25 and its connected ring 22 and bobbin reel 16, as shown in the drawing, comprises a ring gear 40 mounted to freely rotate on the suitably shaped bearing therefor formed on the disc member 17, said ring member carrying a clutch pin variably engageable with said disc member. Ring gear 40 is driven from a vertical shaft 41 mounted in suitable bearings formed on the machine frame and in brackets carried by pillar 12, said shaft having an upper gear 42 meshing with said ring gear 40, and its lower end geared to the machine driving mechanism and arranged to drive said ring gear 40 at the same rotative speed that needle cylinder 2 is driven. The clutch pin 45 mounted in ring gear 40, as shown, is carried by one end of an intermediately pivoted carrying arm 46, the opposite end of said arm having a cam engage-

able head 47 and a spring 48 normally holding said pin 45 in projected position extending through said ring gear to engage one of a series of apertures 50 formed in disc member 17, said apertures preferably having inclined guide ways 51 leading thereto, as shown, and being spaced to correspond with the spacings of the several guide fingers 6, so that each pin engagement with a recess will insure proper position of the guide fingers for action on needles employed in the striping operations.

A lever 55 shown pivoted at 56 to bracket 13, carries a cam 57 adapted to engage head 47 to free clutch pin 45 from engagement with disc 17, and a brake shoe 58, pivotally mounted on pillar 12, is adapted to frictionally engage with disc member 18 simultaneously with the lifting of pin 45 so as to hold said freed carrier reel 16 against rotation. Such joint movements of lever 55 and brake shoe 58 are controlled by a pattern actuated lever 60 connected by a link 61 to one end of a bell crank 62 pivotally supported on the machine frame, the opposite arm of said bell crank having a link 64 connecting it to lever 55, and a separate resilient connection 65 to brake shoe 58. The action of lever cam 57 on head 47 is a momentary one during a portion only of a single rotation of ring gear 40, and is effected in wellknown manner, by the passing of a drum stud 71 beneath one end of lever 60.

Lever 33 is directly connected by its link 34 to a pattern controlled lever 65. The series of jack cams 5 have a corresponding series of directly acting pattern controlled levers 66, and the ring gear clutch pin 45 and bobbin reel brake shoe 58 are jointly controlled as above set forth, by pattern controlled lever 60; and each of said pattern controlled levers is shown as riding in its own respective path on a usual cam drum 70. By properly shaping the cams on said drum 70 and cooperatively timing its joint or sectional rotations, desired selective raising of striping needles into feeding position, and cooperative needle engaging swinging movements of guide fingers 6, may be secured, together with relative change of the guide fingers to the striping needles by timed freeing of clutch pin 45 and its reengagement in a succeeding aperture in disc 17, the bobbin reel 16 during the time such clutch pin is free being held against rotation by brake shoe 58.

The action of jack cams 5 to lift striping needles to a feeding position, is clearly shown in Fig. 4, and to selectively relower certain of such raised needles before the feeding action is affected, as where an interrupted stripe is desired, or where certain stripes are to be omitted as in the foot of a stocking, I have provided a cam 75 fixedly supported on the cam ring 76 and radially shifted bodily into the path of the needle butts by a pattern

controlled lever 77. Said cam 75, as best seen in Figs. 1 and 4, has a pivotal turning movement in its shiftable bearing axle, and is formed with an eccentric needle butt engaging cam edge 80 normally held turned in idle raised position by coil spring 81. When cam 75 is radially shifted toward cylinder 2 by lever 77, a projection 82 on said cam 75 is brought into the path of travel of a cam or 10 cams 83 fixedly secured at proper positions on said rotating needle cylinder. Cam 83, for a part of each rotation of the needle cylinder, will engage and depress projection 82 of cam 75 to turn the latter on its pivot and swing 15 its eccentric edge 80 across the feed level path of travel of the jack raised needles, such temporary position of said edge 80 re-lowering out of said feed level path any raised needles that pass under it. The needles 20 thus relowered will not receive a striping thread in that particular cylinder rotation, but may in the next or a succeeding one, depending on the action of jack cams 5 and of lever 77 controlling the bodily radial shift of cam 75 into and out of the rotary path of cam 83.

Fig. 4 may be read as indicating cam 75 bodily shifted by lever 77 into the path of roller cam 83, and, the turning action of the 30 latter on cam 75 indicated in dotted lines.

The proper timing of the actions of pattern lever 77, and the proper locating of the cylinder carried cams 83 provides additional pattern variations to those produced by the previously described pattern controlled lever 65, series of levers 66, and lever 60.

From the foregoing description it is believed that the nature and operation of my improved construction will be readily understood. And it will of course be recognized that the preferred embodiment thereof specifically set forth may be modified within the spirit of my invention as defined in the following claims.

45 What I claim is:

1. In combination with a circular knitting machine having a rotatable needle cylinder and operative cam mechanism, a striping thread attachment comprising a carrier mounted in axial alinement with said needle cylinder and having a radially swingable needle-engaging thread guide finger, means to rotate said carrier at equal speed with said needle cylinder whereby said guide finger 50 will engage only with certain needles, and pattern controlled means to disengage said carrier and reengage the same in a set-back relation relative to said needle cylinder, whereby said guide finger will engage with other certain needles only.

2. In combination with a circular knitting machine having a rotatable needle cylinder and operative cam mechanism, a striping thread attachment having a rotatable guide finger carrier mounted in axial alinement

with said needle cylinder, a drive mechanism for said carrier comprising a disc member fixed to said carrier and carrying a freely rotatable ring gear member, a clutch pin on one member adapted to variably engage in a series of pin apertures in the other member, pattern mechanism for automatically controlling said variable pin engagements, and means to jointly drive said ring member and needle cylinder. 75

3. In combination with a circular knitting machine comprising a rotatable needle cylinder and operative cam mechanism therefor, a rotatable striping thread guide carrier, means to cooperatively rotate said carrier 80 and said cylinder, and means to disengage said carrier from said rotating means during a determined cylinder rotation and to reengage it in a set-back relation relative to said cylinder before the completion of said 85 determined rotation.

4. In combination with a circular knitting machine comprising a rotatable needle cylinder and operative cam mechanism therefor, a rotatable striping thread guide carrier, means to cooperatively rotate said carrier and said cylinder, and means to disengage said carrier 90 from said rotating means at a definite point in a determined rotation of the needle cylinder, and to reengage the same in a set-back 95 relation relative to said cylinder at another definite point in said cylinder rotation.

5. In combination with a circular knitting machine comprising a rotatable needle cylinder and operative cam mechanism therefor, 100 a rotatable striping thread guide carrier, means to cooperatively rotate said carrier and said cylinder, means to disengage said carrier from said rotating means during a determined rotation of the needle cylinder, means to hold said carrier non-rotative during such disengagement, and means to reengage said carrier in a set-back relative relation to said driving means at a later point 105 in said determined cylinder rotation. 110

6. In combination with a circular knitting machine comprising a rotatable needle cylinder and operative cam mechanism therefor, a rotatable striping thread guide carrier, means to cooperatively rotate said cylinder 115 and carrier comprising a freely rotatable drive member for the latter having a clutch device engageable with any one of a plurality of cooperative clutch devices on said carrier, and means to disengage said clutch from one of said cooperative carrier devices and reengage it in a succeeding one during a determined rotation of said drive member. 120

7. In combination with a circular knitting machine comprising a rotatable needle cylinder and operative cam mechanism therefor, a rotatable striping thread guide carrier, means to cooperatively rotate said cylinder 125 and carrier comprising a freely rotatable drive member for the latter having a clutch 130

device engageable with any one of a plurality of cooperative clutch devices on said carrier, means to disengage said clutch, means to hold said carrier against rotation during such disengagement, and means to reengage said clutch in a succeeding carrier cooperative device, said clutch disengagement and reengagement being automatically effected during a determined rotation of said carrier drive member.

10 In testimony whereof I affix my signature.
FRANK W. ROBINSON.
